PLATE

Carl J. Uhrmann, ½ Imperial Glass Corporation,
Bellaire, Ohio

Filed May 12, 1971, Ser. No. 142,856

Term of patent 14 years

Int. Cl. D7—01

U.S. Cl. D44—15

FIG. 1 is a plan view of a plate showing my new design, a portion of the design being shown between dot and dash lines, it being understood that the ornamentation continues about the surface of the plate in the path indicated by the range of dot and dash lines; and

FIG. 2 is a side elevational view, partially sectionalized, of the plate shown in FIG. 1.

I claim:

The ornamental design for a plate, as shown and described.
